UNITED STATES PATENT OFFICE.

JOSEF Y. DAHLSTRAND, OF WELLSVILLE, NEW YORK, ASSIGNOR TO KERR-TURBINE COMPANY, OF WELLSVILLE, NEW YORK, A CORPORATION OF NEW YORK.

TURBINE DIAPHRAGM AND NOZZLE AND METHOD OF MAKING THE SAME.

1,246,063.

Specification of Letters Patent. Patented Nov. 13, 1917.

Application filed July 28, 1917. Serial No. 183,264.

To all whom it may concern:

Be it known that I, JOSEF Y. DAHLSTRAND, a citizen of Sweden, residing at Wellsville, in the county of Allegany and State of New York, have invented certain new and useful Improvements in Turbine Diaphragms and Nozzles and Methods of Making the Same, of which the following is a specification.

My invention relates to the manufacture of diaphragms and nozzles employed in connection with the rotor element or bucket wheels of any form of fluid impact motor, and more especially to those using the kinetic energy of steam as for example in the ordinary straight Rateau type of multi-stage steam turbine.

The objects of my invention are—

First, to devise a combined diaphragm and nozzle of the character above indicated, in which it will only be necessary to have one mold and one set of cores to carry out a method and produce a diaphragm which can be used to produce all of the several diaphragms with different nozzle areas used in multi-stage or multiple expansion steam turbines, so that different horsepowers with their accompanying rotary speeds and steam conditions can be efficiently satisfied.

Second, to produce a combined diaphragm and nozzle construction which is capable of being kept in stock and later quickly, cheaply and variably finish up the nozzle features as desired, in order to adapt said diaphragm to a particular and specific stage of expansion in an impact multiple expansion steam turbine.

Third, to produce with a simple and single mold and one set of cores a combined diaphragm and nozzle construction and casting, in which the set-in steel vanes adapted to form the maximum nozzle area are cast integral with the body of the semi-steel diaphragm in such a manner, that the similar and finished castings may be made and stocked in great numbers, and any one of these castings can be subsequently machined up, drilled or broached out to produce a diaphragm of any number of nozzles or nozzle area and adapted for use at any point in the various stages of a multi-stage or multiple expansion steam turbine.

Other objects and advantages of the invention will appear from the detailed description and mode of construction and apply the same.

The invention consists of structural characteristics and relative arrangements of the several elements, and method of constructing the invention, which will be hereinafter more fully described and particularly pointed out in the appended claims.

In the two sheets of drawings, wherein is illustrated one embodiment of the invention, and in which similar reference characters indicate the same parts in the several figures of drawings;

Figure 1 is a front elevation and inlet side of the diaphragm cast and made according to my invention.

Fig. 2 is a rear elevation and outlet side of the diaphragm shown in Fig. 1.

Fig. 3 is an enlarged and fragmentary longitudinal section of the finished diaphragms with their nozzles and coöperating bucket wheels of a multiple expansion or 75 multi-stage turbine and taken on line III—III of Fig. 4.

Fig. 4 is a section on line IV—IV of Fig. 3 with the inlet nozzle removed.

Fig. 5 is an enlarged sectional view on 80 line V—V of Fig. 1, or a section on line V—V of Fig. 6.

Fig. 6, is a transverse sectional view on line VI—VI of Fig. 5.

Referring to Figs. 1, 5 and 6, the body 85 10 of the diaphragm is preferably made or cast of semi-steel. In making said diaphragm the usual circular mold for casting the turbine diaphragm has firmly held and placed at suitable and separated intervals 90, preferably throughout two hundred and forty degrees of the circle to cover the usual maximum nozzle area, as shown in Fig. 1, a series of steel vanes or blades 11, 11, each of which vanes or blades consists of a thin 95 piece of steel having its opposite edges preferably parallel and arranged as shown in Figs. 3 and 6, and bent or formed with a straight section 12 and a curved portion 13 as shown in section in Fig. 5, and which is 100 the usual form in order that the nozzles, formed by adjacent blades or vanes will have the proper angle with their coöperating buckets of the adjacent bucket wheel or rotor as shown in Fig. 4. The curved 105 portion 13 of the blades or vanes 11, 11, are disposed toward the front or inlet side and the straight section 12 toward the outlet side of the diaphragm 10.

Between the blades or vanes 11, 11, while 110

properly supported and secured in position in the mold for casting the diaphragm as explained above, are placed sand cores as is usual in turbine diaphragm nozzle casting, 5 but in the present invention and one of the most important features thereof, the said cores are stopped off, or fall short the thickness of the bridge sections 14, 14, see Figs. 5 and 6, from the outlet ends of the blades 10 or vanes 11, 11, or plane of the outlet side 15 of the diaphragm, so that when the molten semi-steel is poured into the mold having the said cores and blades or vanes 11, 11, arranged as above described, the metal forming the body of the diaphragm 10 is cast about and integrally surrounds the series of separated blades or vanes 11, 11, thereby firmly and rigidly holding the blades or vanes in their proper angular and spaced 20 relation to each other and to the body of the diaphragm.

In the finished casting of the diaphragm shown in Figs. 1, 2, 5 and 6, the spaces between the blades or vanes 11, 11, adjacent or 25 near their outlet ends and which were not occupied by the sand cores, are filled with the said semi-steel bridge sections 14, 14, and as will be readily understood, plug or close up the outlets of the passageways 30 formed between the series of separated blade or vanes 11, 11, see Figs. 2, 5 and 6, and said bridges or plugs 14, 14, occupying sections of the nozzles, will be later removed in various degrees and in any desirable 35 manner as occasion requires, and form the desired nozzle area or outlets of the finished combined diaphragm and nozzles for a particular stage of expansion and for purposes to be presently described.

40 It will also be easily understood and readily suggested to any one skilled in the art, that if a circular core shaped to the space not occupied by the metal of the diaphragm shown in Figs. 1 and 2, said core having embedded or supported therein the semi-steel vanes or blades 11, 11, in their proper relation, were correctly placed in a mold of the outer contour of the diaphragm body 10, within the usual founder's 45 flask, and said mold with above described core poured with molten semi-steel, and after the poured metal had sufficiently cooled to permit the sand core to be removed, the resultant casting would be a similar combined diaphragm body 10 and spaced blades or vanes 11, 11, having the semi-steel bridge sections 14, 14, between the outlet ends of 50 said vanes or blades 11, 11, as shown in Figs. 1, 2, 5 and 6.

55 It will be readily understood that while I have shown and described as my preferred form of cast diaphragm the bridge sections 14, 14, as being at the outlet end of the nozzles and flush with the plane of the outlet 60 side of the diaphragm, I do not care to limit

myself to this particular construction and arrangement, as said bridge sections or plugs 14, 14, could be placed at any other point between the inlet and outlet ends of the blades or vanes 11, 11, without departing from the spirit of my invention and fully carry out all the novel and essential features of the same, as long as said bridge sections or plugs 14, 14, prevent the formation of separated passageways through the 70 diaphragm from its inlet side to the outlet side. 75

Assuming many diaphragms 10 are in stock which have been cast as heretofore explained and of the construction shown in 80 Figs. 1, 2, 5 and 6, and an order is received to build a turbine of certain horsepower, having initial steam pressure, rotary speed and other conditions given, as for example three stages of expansion, as diagrammatically illustrated in Figs. 3 and 4, one of the diaphragms 10' has two of its bridge sections or plugs 14, 14, removed to form two completed and distinct nozzles 15 and 15, diaphragm 10² has three plugs or bridge sections 14, 14, 14, drilled out thereby producing three independent nozzles 16, 16 and 16, and diaphragm 10³ has four sections 14, 14, 14, and 14, broached out and hence creating four separate nozzles 17, 17, 17 and 17, 90 said nozzles 15, 16 and 17 acting on bucket wheels W¹, W² and W³, respectively, as will be understood by those skilled in the art and needing no further explanation. 95

If further stages of expansion are desired 100 diaphragms having five, six or more bridge sections or plugs 14, removed may be added, until the limit or maximum number arranged within the diaphragm are employed.

105 It will also be seen that should it be desired to change the form or radial depth of the nozzle or passages between the semi-steel blades or vanes 11, 11, to satisfy certain conditions of initial steam pressure, rotary speeds, size of buckets on the rotor or 110 other variable conditions, and at the same time preserve the high efficiency of the turbine, this can be readily and cheaply accomplished without in any way modifying the invention, by simply drilling or removing 115 in any way the additional metal between the blades or vanes 11, 11, so that the cross-sections of the nozzles or passageways will be of the form shown in diaphragms 10² and 10³, of Fig. 3. While I have particularly described and shown my invention as applied to the use of steam turbines, I do not limit myself to this specific application 120 as the same could be adapted for other and similar motors wherever a fluid or gas is made to pass through a plurality of nozzles in one, or a series of successive stages, and said fluid or gas after passing through the nozzles impinges upon the buckets of a rotor member. 125 130

From the foregoing disclosure of construction and mode of carrying out the improvements, it will be seen that all the functions and advantages of the same set up in 5 the statement of invention are fully and efficiently carried out at a minimum of cost, time in production and installation, while at the same time greatly reducing the number of patterns, stock of manufactured parts 10 to be kept on hand, and floor space occupied by the same for a given output of a turbine manufacturing plant.

What I claim is:—

1. A circular casting to be used in the 15 manufacture of a diaphragm adapted for use at any stage of expansion of a multi-stage or multiple expansion impact turbine comprising a body section having a series of separated, independent and obstructed 20 nozzle passageways arranged in the arc of a circle and near its periphery.

2. A circular flat casting to be used in the 25 manufacture of a diaphragm adapted for use at any stage of expansion of a multi-stage or multiple expansion impact turbine comprising a body section having a series of separated, independent and obstructed 30 nozzle passageways arranged in the arc of a circle near its periphery and at an angle to the opposite flat faces.

3. A circular flat casting to be used in the 35 manufacture of a diaphragm adapted for use at any stage of expansion of a multi-stage or multiple expansion impact turbine comprising a body section having a series of separated and independent nozzle passageways arranged in the arc of a circle near its periphery and at angle to the opposite flat faces and a plug or bridge section in 40 each of said nozzle passageways flush with one of said flat faces.

4. A circular casting to be used in the 45 manufacture of a diaphragm adapted for use at any stage of expansion of a multi-stage or multiple expansion impact turbine comprising a body section provided with opposite flat faces forming its inlet and outlet sides and having cast integral therewith a series of separated blades or vanes arranged 50 near the periphery and at an angle to the said opposite flat faces of the diaphragm and later capable of forming a plurality of nozzle passageways through and from the inlet to the outlet sides of the diaphragm, 55 and a removable bridge or plug section interposed between the inlet and outlet ends of each of said nozzle passageways.

5. A circular casting to be used in the 60 manufacture of a diaphragm adapted for use at any stage of expansion of a multi-stage or multiple expansion impact turbine comprising a body provided with opposite flat faces forming its inlet and outlet sides

and having cast integral therewith a series of separated blades or vanes arranged in 65 the arc of a circle near the periphery and at an angle to the said opposite flat faces of the diaphragm and later capable of forming a plurality of nozzle passageways through and from the inlet to the outlet sides 70 of the diaphragm, and a removable bridge or plug section interposed between the inlet and outlet ends of each of said nozzle passageways.

6. A circular casting to be used in the 75 manufacture of a diaphragm adapted for use at any stage of expansion of a multi-stage or multiple expansion impact turbine comprising a body section provided with opposite flat faces forming its inlet and outlet sides and having cast integral therewith a series of separated blades or vanes arranged near the periphery and at an angle to the said opposite flat faces of the diaphragm and later capable of forming a plurality of nozzle passageways through and from the inlet to the outlet sides of the diaphragm and a removable bridge or plug section at the outlet end of each of said nozzle passageways.

7. The method of making a diaphragm 90 for the various stages of a multi-stage or multiple expansion type of turbine consisting of casting a circular flat disk provided with a series of separated and independent 95 incomplete passageways or nozzles, each of said nozzles or passageways having a bridge or plug between its ends, said nozzles or passageways being at an angle to and extending from the opposite flat faces of 100 the diaphragm, and removing a plurality of said bridges or plugs from the nozzles or passageways depending upon what stage of expansion the diaphragm is to be used in the turbine or what cross sectional area 105 of the nozzle is desired.

8. The method of making a diaphragm 110 for the various stages of a multi-stage or multiple expansion type of turbine consisting of casting a circular flat disk having parallel inlet and outlet faces and provided with a series of separated and independent 115 incomplete passageways or nozzles, each of said nozzles or passageways having a bridge or plug flush with the outlet face, said nozzles or passageways being at an angle and extending between said inlet and outlet faces of the diaphragm, and removing a plurality of said bridges or plugs from the nozzles or passageways depending upon what stage 120 of expansion the diaphragm is to be used in the turbine or what cross sectional area of the nozzle is desired.

In testimony whereof, I affix my signature.

JOSEF Y. DAHLSTRAND.
